UNITED STATES PATENT OFFICE.

GEORGIANA SYMMS, OF LE MARS, IOWA.

DESIGN FOR A CARD-HOLDER.

SPECIFICATION forming part of Design No. 24,377, dated June 11, 1895.

Application filed April 12, 1895. Serial No. 545,531. Term of patent 7 years.

To all whom it may concern:

Be it known that I, GEORGIANA SYMMS, a citizen of the United States, residing at Le Mars, in the county of Plymouth and State of Iowa, have invented and produced a new and original Design for Card-Holders; and I do hereby declare the following to be a full, clear, and exact description of the same, reference being had to the accompanying drawings, forming a part thereof.

In the drawings, Figure 1 is a front elevation of my design, and Fig. 2 is a side elevation thereof.

Like characters of reference indicate the same parts in both views.

My design consists of back A and front B, representing a continuous piece of metal or other suitable substance having its widest part near the center, tapering toward the ends,

the portion intended for the front tapering less than the portion intended for the back. The front B is returned upon the back A forming a loop as shown in Fig. 2. The tops of the front and back are scalloped being surrounded by the lobes c, d, e and f, g, h, the lobes c, e and f h extending beyond the sides of the front and back respectively, and the central lobes d and g projecting above the side lobes, as set forth.

What I claim is—

The design for a card holder herein shown and described.

In testimony whereof I affix my signature in presence of two witnesses.

GEORGIANA SYMMS.

Witnesses:

WM. M. CLAGG,
CHAS. H. SPERLING.
